KEYLESS LOCK.

1,071,510.

Specification of Letters Patent. Patented Aug. 26, 1913.

Application filed May 19, 1913. Serial No. 768,649.

To all whom it may concern:

Be it known that I, DANIEL W. CROCKETT, a citizen of the United States, residing at Indianapolis, in the county of Marion 5 and State of Indiana, have invented certain new and useful Improvements in Keyless Locks, of which the following is a specification.

This invention relates to keyless locks, 10 and in order to illustrate a lock in operative form I have selected, from a large variety of devices with which a lock of the above character may be employed, a gear shift lever for motor cars to which same is 15 particularly applicable.

The object of the invention consists in the provision of a lock of the above character wherein the use of keys is dispensed with, and while it is almost impossible for unauthorized persons to manipulate the lock 20 the same can be easily operated by persons knowing the combination thereof.

A further object of the invention consists in the provision of a lock of the above character wherein the dials will be automatically moved from their set positions preceding the act of opening the lock, so that the positions 25 of the dials, for unlocking the lock, can not be ascertained by unauthorized persons.

30 A further object of the invention consists in the provision of a lock of the above character wherein the combination of the dials cannot be changed when the lock stands in a locked position.

35 A further object of the invention consists in the provision of a lock of the above character in which the combination may be easily and quickly changed by an authorized person, thereby decreasing the liability of 40 the lock being opened by a person who may have surreptitiously secured the unlocking combination of the lock.

I accomplish the above objects of the invention by means of a keyless lock illustrated in the accompanying drawings, forming 45 a part hereof, in which—

Figure 1 is a front elevation of the keyless lock showing the slidable cover plate partially in elevation. Fig. 2 is a view similar 50 to Fig. 1, except that the face plate has been removed to expose the internal mechanism of the lock. Fig. 3 is a view similar to Fig. 2, except that the dials have been removed so as to expose the mechanism beneath. Fig. 55 4 is a view similar to Fig. 2, except that the

positions occupied by the parts are shown when the bolt is thrown. Fig. 5 is a central vertical sectional view through the lock on the dotted line 5—5 in Fig. 2. Fig. 6 is a cross section of the lock on the line 6—6 60 in Fig. 1. Fig. 7 is a cross section of the lock seen from the dotted line 7—7 in Fig. 2. Fig. 8 is a side elevation of the dial, pinion and ratchet wheel, the surrounding parts of the lock being omitted. Fig. 9 is 65 a top or plan view of the construction shown in Fig. 8. Fig. 10 is a view showing the lock employed in connection with a gear-shift lever as commonly employed on motor cars. Fig. 11 is a cross section of the gear-shift lever and the bolt of the lock on the dotted line 11—11 in Fig. 8.

Referring to the drawings, the bolt and other internal mechanism of the lock are located within a suitable casing or housing 75 comprising the parallel side members 15, end members 16 and 17 and the bottom member 19, the casing being open at the top to admit the insertion of the lock mechanism. After the mechanism of the lock 80 has been placed into position within the casing the top of the casing is closed by means of a face-plate 20.

Located within the casing of the lock and sliding upon the bottom member 19 thereof 85 is a bolt 22, which bolt extends externally of the casing through a suitable opening in the end wall 17 of the casing. The opposite end of the bolt 22 terminates in a stem 23 which may be grasped by the hand and by 90 which a longitudinal movement may be imparted to move the end of the bolt externally of the casing or to retract it. The operation of the bolt 22 is regulated and controlled by means of a plurality of dials 95 28 carrying suitable scales to enable said dials to be moved into predetermined positions, thereby enabling the bolt 22 to be moved longitudinally into and out of the keeper or other device with which said bolt 100 makes engagement.

As shown in Fig. 3 of the drawings, the bolt 22 is provided centrally with an aperture to allow the positioning of the posts 25 mounted on the bottom member 19. The bolt 22 is normally held into contact with the bottom member 19 by means of a leaf spring 24. The posts 25 form bearings for the dials 28. Each of the dials 28 is provided with a hub extension 29, (see Fig. 8) 110

which hubs are reduced in diameter to form the shoulders 30 upon which suitable disks 33 ride. The hub extensions 29 below the faces of the disks 33 are provided with the 5 pinions 34 and the ratchet wheels 35 which are secured thereto and rotate therewith. Each of the disks 33 carries a toothed pawl 37, and the pawls are normally held into engagement with the pinions 34 by means 10 of the springs 45, whereby said disks are normally forced to simultaneously rotate with the dials 28. The pawls 37 may be moved out of engagement of the pinions 34 to enable the dials 28 to be moved independently of the disks when it is desired to 15 change the relative positions of the disks with respect to the dials when a new combination or starting point, for permitting the bolt of the lock to be moved longitudinally 20 for unlocking the lock, is desired. A further description of this construction will later appear.

Each of the disks 33 is provided with a primary peripherally located notch 40 25 adapted to be engaged by suitable lugs 41 formed integrally on the bolt 22. When the disks 33 have been rotated to bring said notches into registration with the lugs 41 the bolt 22 is free to be moved longitudinally 30 into or out of engagement of the keeper or other device with which it makes engagement.

As before stated, after the mechanism has been placed in the casing of the lock the 35 same is inclosed by means of a face-plate 20 and said plate is provided with suitable apertures 43 to allow the dials 28 to be exposed to view, and in operative position the surfaces of the dials 28 stand flush with 40 the surface of said face-plate. The face-plate 20 and the dials 28 are further inclosed by means of a slidable cover-plate 47 which slides in suitable ways or grooves 48 in the side walls 15 of the casing.

45 As heretofore stated, the hub extensions 29 of the dials 28 carry pinions 34 and ratchet wheels 35. The pinions are engaged by means of suitable toothed pawls 37 (see Fig. 9), which slide in a groove 38 in the disks 33, and said pawls are normally held into engagement with the pinions 34 by means of springs 45. In normal operative position, by reason of the pawls 37, the disks 33 are forced to rotate with the dials 28, 55 whereby the primary notches 40 in the disks may be brought into registration with the lugs 41 on the bolt 22.

In case it is desired to change the combination for opening the lock it becomes necessary to temporarily hold the disks 33 stationary while the dials 28 are moved into a new position with respect to the disks 33, thereby necessitating the dials to be moved into a new position to bring the primary 60 notches 40 into registration with the lugs

41 before the lock can be opened. To accomplish this purpose of temporarily holding the disks 33 when it is desired to arrange a new combination, I provide a movable actuator-arm 50 for each disk 33. 70 These actuator-arms are pivotally secured to a post 52 mounted on the bottom member 19 of the casing. The actuator-arms 50 are each provided with downwardly extending lips 53 which hook down over and engage suitable shoulders 37^a formed on the pawls 37, so that in moving the actuator-arms outwardly away from the axes of the disks 33 the pawls 37 will be disengaged from the pinions 34. The actuator-arms 50 75 are provided with suitable vertically disposed pins 55 which project through suitable slots 56 in the face-plate 20, so that said actuator-arms 50 are accessible and may be moved from the top of the face-plate 20 80 of the lock. It may be stated, however, that the actuator-arms 50 can only be moved so as to disengage the pawls 37 from the pinions 34 when the bolt 22 stands in a retired position and the lock is open, that is to say, 85 when the bolt 22 is disengaged from its keeper, and said arms cannot be moved to disengage them from the pawls 37 when the bolt 22 is shot. To accomplish this I provide a U-shaped member 58 which moves 90 with the bolt 22, the bent ends of said member 58 being moved out of contact of the enlarged portions 59 on the actuator-arms 50. By means of this construction the combination of the lock can only be changed 95 when the lock is open, thereby preventing disarrangement of the combination when the lock is locked. This may be desirable 100 for many reasons. When the bolt 22 of the lock is in its shot position the bent ends of 105 the U-shaped member 58 will be moved in front of the enlargements 59 on the actuator-arms 50, whereby the latter are prevented from being moved out of engagement of the pawls 37. The actuator-arms 50 are normally held into engagement with the pawls 37 by means of suitable springs 60. 110

The outer sliding cover-plate 47 may be locked in its open extended position to prevent the same from being entirely removed 115 from the casing. This is accomplished by providing spring mounted pins 62 and 63 in the end of the face-plate 20, which pins are actuated by the movement of the bolt 22 and movable bar 70 so as to force said pins upwardly into the grooves or notches 64 and 65 within the face-plate 47 when the bolt stands in certain positions.

It has heretofore been pointed out that it is desirable and in fact necessary to destroy 120 the relative positions of the dials 28, determining the combination to unlock the lock when the device is locked, otherwise any person could pull the bolt 22 out of engagement of the keeper. Therefore, to 125

move the dials 28, I provide a movable bar 70 which rides upon the bolt 22, and said bar has movement independently of the bolt, which is permitted by means of the slots 71 and screws 72. This movable bar 70 carries the pawls 75 which are pivotally mounted on the studs 76, the latter being fixed on the bar 70.

When the lock is open and the bolt stands in its retracted position the free ends of the pawls 75 stand engaged with the toothed edges of the ratchet wheels 35, under the influence of the spring 79. When the bolt is shot the pawls 75 are moved out of engagement of the ratchet wheels 35. The oscillatory movement of the pawls around the pins 76 is limited by means of the stops 78. When the bolt 22 is moved in its outermost position, the bar 70 will have a slightly delayed movement caused by the resistance offered by the disks 33 and the dials 28. A slight tension is applied to the bar 70 to move it in the direction in which the bolt 22 is shot, under the action of the spring 80. The spring 80 is secured at one end to a post 81 mounted on the bar 70 and the other end of the spring is secured to a post 82 mounted on the bolt 22, so that when the bolt 22 is moved in its outermost position the spring 80 will be extended to apply a greater pull on the bar 70 until the tension of the spring overcomes the resistance offered by the disks 33 and the dials 28 when the bar 70 will start suddenly and move in the direction in which the bolt is shot. During this movement of the bar 70 the ends of the pawls 75 will be suddenly disengaged from the ratchet wheels 35, thereby causing the disks 33 and dials 28 to continue to rotate a short distance, so that the positions of the disks, in attaining the combination, for unlocking the lock, are changed. This construction will prevent the lock from being opened unless by some one who is familiar with the combination of the lock.

Having thus fully described my said invention, what I desire to secure by Letters Patent, is—

1. A keyless lock comprising a casing, a latch bolt moving longitudinally within said casing, a lug on and moving with said latch bolt, a rotatable disk provided with a peripheral notch adapted to be brought into registration with the lug on the latch bolt, a dial for mounting said disk, a ratchet wheel rotating with said dial, a movable bar arranged on said bolt, a pawl carried by said bar adapted to engage said ratchet wheel when the bolt stands in unlocked position and to rotate said ratchet wheel out of engagement with said pawl when the bolt

is shot, and means for exerting a tension for moving the bar in the direction in which the bolt is shot.

65

2. A keyless lock comprising a casing, a latch-bolt moving longitudinally within the casing, a lug on said bolt, a revoluble dial arranged in advance of said bolt, means for mounting said dial, a disk wheel, provided with a peripheral notch adapted to receive the lug on the latch-bolt, carried by said dial, a pinion moving with said dial, a pawl carried by said disk to engage the pinion, means for normally holding said pawl into engagement with said disk, an operative lever for moving said pawl out of engagement of said pinion, means on said operative lever extending above the face of the lock to permit the pawl to be operated externally of the lock when the lug engages a notch in the disk, and means moving with the latch-bolt for arresting the movement of the operative lever when the bolt is shot.

80

3. A keyless lock comprising a casing, a latch-bar moving longitudinally within the casing, means for longitudinally moving said latch-bolt, a cover-plate slidably arranged in the casing and provided with a recess in its under surface, a pin arranged in the end wall of the casing, and means for normally holding said pin against the face of said latch-bolt.

85

4. A keyless lock comprising a casing, a latch-bolt moving longitudinally within said casing, means for longitudinally moving said latch-bolt, a movable bar carried by said latch-bolt, a pin arranged in the end wall of said casing, and means for normally holding said pin into the path traveled by said movable bar.

95

5. A keyless lock comprising a casing, a latch-bolt moving longitudinally within said casing, a lug on said latch-bolt, a dial arranged in advance of said latch-bolt, means for mounting said dial, a disk provided with a peripheral notch carried by said dial, a ratchet wheel moving with said dial, a movable bar arranged on said latch-bolt, a pawl on said movable bar to engage said ratchet wheel, means for normally holding said pawl inwardly into the path of the ratchet wheel, and means for limiting said inward travel of said pawl.

105

In witness whereof, I, have hereunto set my hand and seal at Indianapolis, Indiana, this, 19 day of April, A. D. one thousand nine hundred and thirteen.
